JULIUS SCHMID, OF NEW YORK, N. Y.

NURSING NIPPLE

Application filed October 20, 1930. Serial No. 489,763.

This invention relates principally to rubber nipples such as are employed upon nursing bottles, and to other similar rubber articles. In the manufacture of nipples and the like 5 from transparent rubber, it is highly desirable that the name, trade-mark or brand of the manufacturer be applied to the nipples in order that their source of origin may be carried thruout the channels of trade, not 10 only as a guarantee of quality but also for facilitating the re-ordering of the goods.

Considerable difficulty has been experienced in the past in applying a trade or brand name to the nipple, as it has not been generally regarded as possible to stamp the brand or trade name in ink or other pigments on either the outside or the inside of the nipple.

There is a grave liability involved in either course of procedure. If the brand name or 20 trade-mark is stamped on the outside of the nipple, the nursing child is likely to come in contact with it and thus run the danger of being made ill by some of the ingredients of the pigment or ink employed in the lettering.

Similarly, if the brand or trade-mark were printed or stamped on the inside of the nipple there would be danger of contaminating the contents of the bottle.

30 Also a further objection would arise in both cases, from the fact that the sterilization of the nipple or the subjection of it to high degrees of heat would result in the defacing or wearing away of the trade-mark or 35 brand name.

The object of the present invention is to overcome the foregoing objections and difficulties, and this is attained by providing means for marking the brand or trade name 40 of the nipple thereon in such manner that it is permanent, wears as long as the nipple, and is absolutely sanitary as regards both the mouth of the child and the contents of the bottle.

45 The invention resides in the combination and arrangement of parts and the details of construction as hereinafter described and claimed, it being understood that changes in the embodiment of the invention herein 50 disclosed may be made within the scope of

what is claimed and as indicated by the variations between the different claims without departing from the spirit of the invention.

In the accompanying drawings forming 55 part of this specification:

Figure 1 is a side elevation of one of the improved nipples.

Figure 2 is a similar view, with the casting of the nipple partly cut away and shown 60 in sections, and with the reinforcing band illustrated in the elevation.

Figure 3 is a view of a strip of rubber adapted for forming the reinforcing bands.

Figure 4 is a view showing the reinforcing bands after they have been rolled into 65 tubular form.

Like reference numerals indicate corresponding parts in the different figures of the drawings.

70 The improved nipple of this invention comprises the nipple proper, 1, and the reinforcing neck band 2.

The neck band preferably is formed as 75 shown in Figure 3, wherein a strip of rubber has a trade-mark or brand stamped on the various sections thereof, which sections are then cut off along the dotted line and rolled into tubular form and vulcanized in any suitable manner inside of the neck part 3 of 80 the nipple.

The result is that the brand name or printing is vulcanized in between the reinforcing band 2 and the neck portion 3, so that the trade-mark or brand name is disclosed to 85 sight thru the transparent material of the nipple and yet the letters or ink are thoroughly insulated from both the outside and the inside of the nipple and may not be removed therefrom by contact with the lips or with hot fluids or thru the process of handling the bottle or applying the nipple thereto.

90 By making the nipple in the manner heretofore described the trade-mark or brand becomes a non-effaceable part of the nipple 95 and its life is co-incident with the life of the nipple.

What is claimed as new is:—

1. A rubber nipple comprised of a body, 100 and a neck portion, said neck portion being

transparent, a reinforcing neck band vulcanized with the neck portion of the nipple and carrying thereon indicia printed in ingredients which are insulated both exteriorly and interiorly of the nipple, said indicia being exposed to view through said transparent portion.

5 2. A rubber nipple having a transparent portion, and a reinforcing band vulcanized with said portion of the nipple and carrying thereon indicia printed in ingredients which are insulated both exteriorly and interiorly of the nipple, said indicia being exposed to view through said transparent portion.

10 15 JULIUS SCHMID.
